US0D1034816S

(12) **United States Design Patent** (10) Patent No.: **US D1,034,816 S**
(45) Date of Patent: ** Jul. 9, 2024

(54) **VIDEO GAME CONTROLLER**

(71) Applicant: **Performance Designed Products LLC**,
San Diego, CA (US)

(72) Inventors: **Thomas John Roberts**, Alpine, CA
(US); **Trevor Thomas Lehr**, Alpine,
CA (US); **Ali Homayounfar**, San
Diego, CA (US)

(73) Assignee: **Performance Designed Products LLC**,
Burbank, CA (US)

(**) Term: **15 Years**

(21) Appl. No.: **29/792,137**

(22) Filed: **Mar. 7, 2022**

(51) LOC (14) Cl. **21-01**

(52) U.S. Cl.

USPC **D21/333**

(57) **CLAIM**

The ornamental design for a video game controller, as shown and described.

DESCRIPTION

FIG. 1 is a top perspective view of a video game controller embodying my new design, according to a first embodiment;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

In the drawings, the broken lines depict portions of the video game controller that from no part of the claimed design.

1 Claim, 5 Drawing Sheets
